Application August 29, 1939, Serial No. 292,402

18 Claims. (Cl. 66—86)

This invention relates to knitting machines and is concerned more particularly with a novel knitting machine of the warp type which is provided with means for balancing the operation of various parts which are given non-rotary movements during fabric production.

Warp knitting machines include knitting elements made up of needle-bar, sinker-bar, presser-bar, and guide-bar assemblies which are driven by cams on a common driven shaft and receive rapid non-rotary movements therefrom. As the assemblies extend the full length of the machine, which may vary from six to fifteen feet in ordinary practice, and have substantial mass, their non-rotary movements produce forces which cause each assembly to vibrate, and the combined vibrations cause the entire machine to shake and rock. Such vibrations may impair the quality of the cloth produced and, in any case, limit the speed at which the machine may be safely operated.

In order to produce knit fabrics on such machines at a high rate of production, attempts have been made to reduce the vibration of the machine by balancing the various parts which are required to perform rapid, non-rotary motions. In one prior method of balancing, each knitting element assembly incorporates balancing masses distributed along the length of the machine and equal in number to the number of points at which each non-rotary member is driven. Each balancing mass oscillates about the same axis as the mass it balances and it is arranged at the same effective radius as the mass it is to balance and given movements precisely similar in velocity, but in the opposite sense, so as to effect neutralization of the vibrational forces.

Such a system of balancing necessitates the incorporation of numerous balancing masses in each knitting assembly, and as there are four such assemblies in knitting machines of the type described, a great many balancing masses are required. The disadvantage in the use of a multiplicity of balancing masses for each assembly is that it complicates the design of the machine and greatly increases its cost of manufacture. Furthermore, in machines of this type, one or more guide bars may be required, depending on the pattern to be produced in the fabric, and each guide bar adds additional weight to the guide bar assembly and thus requires additional balancing masses. For example, if the machine is balanced for one guide bar and two bars are required to knit a particular pattern, additional balanc-

ing masses must be added to the assembly to secure smooth running of the machine. If the next pattern to be knitted requires only one guide bar, the additional masses must be removed. The addition or subtraction of balancing masses, depending on the number of guide bars used, further complicates the operation of the machine.

The present invention is, accordingly, directed to the provision of a novel mechanism for balancing knitting machines which overcomes the objections to the prior apparatus above described, and is greatly superior thereto in that the new mechanism accomplishes the desired purpose without each knitting assembly being individually balanced. At the same time, the new mechanism may be employed on machines using one or more guide bars, and the change in the number of guide bars does not materially affect the resultant balance of the machine, so that the necessity of changing balance weights is avoided.

The new mechanism includes rotary balancing means arranged to rotate continuously and uniformly at a speed which is multiple of the cam shaft speed, and included in the rotary balancing means are suitable balancing masses. The balancing masses are placed at suitable radial distances from their centers of rotation and in proper angular position with respect to each other so that they produce, on rotation, forces which tend to neutralize certain components of the forces produced by the non-rotary motions of the knitting assemblies and thus substantially reduce the forces causing the machine to vibrate.

In the operation of warp knitting machine of the type described, the knitting assemblies operate at a fixed time relation to each other that cannot be materially changed and produce satisfactory fabrics. Because of the fixed relation, the various assemblies cannot be so timed in their phase relation to each other that the various motions produce forces that neutralize each other. As a consequence, the vibrational forces produced by each of the non-rotary motions of the knitting assemblies result in complex harmonic forces that cause the entire machine and its parts to vibrate. We have found that these resultant complex forces contain a large component of double frequency up to certain speeds, while at certain higher speeds the third harmonic will occur, and as the speed is increased, the fourth and higher harmonics occur. The second harmonic is found to occur at one range of speeds desirable for high speed operation of the knitting machine, and at the next desirable range of speeds, the third harmonic occurs. We have found further that ro-

tary balancing means, which include balance weights, rotated at twice the speed of the cam shaft will produce forces that substantially neutralize the double frequency component of the complex forces produced by the non-rotary motions of the knitting assemblies. In like manner, rotating the balancing means at three times the cam shaft speed will substantially neutralize the third harmonic component. Under certain conditions, a combination of means for neutralizing the second and third harmonic may be desirable.

By reducing the component of the forces producing the second and third harmonics, the resultant forces cause very little vibration in the machine and its smoothness in operation is greatly increased. In some cases, the introduction of a harmonic couple, comprising balance weights mounted 180 degrees out of phase with each other and rotated at a multiple of the cam shaft speed, in combination with separate rotary balancing means rotating at a multiple of the cam shaft speed, will materially reduce the vibrational forces causing the machine to vibrate.

To make clear the principles of the invention, an embodiment will be illustrated in the form of a two bar knitting machine including rotary balance weights producing forces that substantially neutralize the second harmonic component produced by the non-rotary motions of the knitting assemblies, together with a harmonic couple, the combination substantially reducing the forces causing the machine to vibrate.

Referring now to the drawings:

Figure 1 is a view, partly in side elevation and partly in transverse section, of a warp knitting machine embodying the present invention and showing the locations of the knitting elements and of the rotary balancing devices;

Figure 2 is an enlarged detail sectional view showing the knitting assemblies with certain parts omitted;

Figure 3 is a front view in elevation of a portion of the machine showing the location of the balancing masses; and

Figure 4 is a detail view, showing a modification.

Referring to Figures 1 and 2, the machine as there illustrated comprises a frame 10, the upper portion of which supports two warp beams 11 and 12. Warp threads 14 and 15 are drawn from the beams 11 and 12 and pass over tension bars 16 and 17 to thread guides 18 and 19 carried by guide bars 20 and 21, the guides directing the threads to the needles 22 carried on needle bar 23. The threads are knitted into a fabric by the interaction of the two rows of guides 18 and 19, needles 22, sinkers 24 carried on bar 25, and presser 26 carried on bar 27, and the fabric 28 proceeds from the needles 22 to a take-up device 29.

The guide bars 20 and 21 extend the whole length of the machine and, as shown, are secured by suitable connections to a shaft 30 supported by the framework of the machine. The guide bar assembly is caused to pass through its knitting cycle by the oscillation of shaft 30, which is driven by one or more cam levers 31 free to oscillate on a shaft 32 supported by the framework of the machine. Oscillatory motion requisite for knitting is imparted to levers 31 by cam rollers 33 and 34 mounted thereon and riding on the surfaces of cams 35 fast on cam shaft 36 supported by the framework of the machine. There is a cam on shaft 36 for each cam roller in the guide bar drive and in the drives for the

other knitting element assemblies but one of the cams has been omitted in each case for clearness in illustration.

The needle bar 23 extends the whole length of the machine and is supported at various points by arms 37 fast on shaft 32. Oscillatory motion requisite for knitting is imparted to arms 37 and needle bar 23 by cam rollers 38 and 39 mounted on the arms and riding on the surfaces of cams 40 fast on cam shaft 36. The sinker bar 25 also extends the whole length of the machine and is supported at various points by arms 41 fast on shaft 41 supported by the framework of the machine. Oscillatory motion requisite for knitting is imparted to the sinker bar by arms 42 fast on shaft 41, the arms carrying cam rollers 43 and 44 riding on the surfaces of cams 45 fast on cam shaft 36. The presser bar 26 likewise extends the whole length of the machine and is supported at various points by connections fast on shaft 46 supported by the framework of the machine. Oscillatory motion requisite for knitting is imparted to the presser bar by arms 46 fast on the shaft 46 and carrying cam rollers 47 and 48 riding on the surfaces of cams 49 fast on the cam shaft 36. The above described mechanism for imparting oscillatory motions to the various assemblies requisite for knitting is, in general, common to warp knitting machines of the type described.

The rotation of the cam shaft 36 causes the various cams to impart the requisite non-rotary motions to the knitting assemblies in the production of knitted fabrics and these non-rotary motions of the knitting assemblies produce vibrations in the assemblies themselves. As a result of these vibrational forces, the framework of the machine is caused to rock and shake and the smoothness of the operation of the machine is thereby seriously affected. Such vibration varies with the speed of operation and places a limit on the machine output.

In one embodiment of the invention as applied to a two bar machine operating at speeds which cause the second harmonic to occur, the cam shaft 36 is given a continuous and uniform rotary motion from any suitable driving means, such as an electric motor 50 supported by the framework of the machine. A pulley 51 on the motor shaft is connected by belt 52 to a pulley 53 fast on a hand wheel shaft 54 supported by suitable bearings on the framework of the machine. Fast on the shaft 54 is a sprocket 55 connected by a chain 56 to a sprocket 57 fast on the cam shaft 36. In applying the principles of the invention to eliminate the second harmonic, the driving means for shaft 54 is such that the shaft is driven at twice the cam shaft speed and at suitable points on the shaft 54 are mounted discs 58 carrying balance weights 59. Hand wheel 60 fast on the shaft 54 serves as a convenient means for rotating the cam shaft and the associated knitting assemblies by hand.

The preferred form of the harmonic couple constituting the auxiliary balancing means includes a shaft 61 adjacent the location of the oscillating shaft 30, as shown in Figure 3. The shaft 61 is mounted in a bearing 62 supported by the framework of the machine and fast on this shaft is a sprocket 63 connected by a chain 64 to a sprocket 65 fast on the cam shaft 36. At suitable points on the shaft 61 are mounted discs 66 carrying balance weights 66^a and 67. The sizes of the sprockets are such that the shaft 61 is driven at twice the speed of the cam shaft 75

36 and thus produces vibrational forces of the second period. In the particular embodiment illustrated in Figure 3, the weights 66^a and 67 are mounted 180 degrees apart to produce a couple. In some cases, it may be desirable to mount the weights in phase and spaced apart to produce the vibrational forces required.

By properly selecting the pairs of balance weights 59 on the shaft 54 and of weights 66^a and 67 on the shaft 61 with respect to size, radial distance from their centers of rotation, angular relation to each other, and distance apart, neutralizing forces are produced, which may be illustrated graphically in the form of two second period harmonic curves of an amplitude, corresponding to the masses of the weight, superimposed on the complex harmonic curve of the vibrating machine. By this method of balancing, the resultant vibrational forces are substantially reduced, and this reduction materially reduces the vibration of the machine, enables the machine to be operated at high rates of speeds, and produces a smoothness in operation not heretofore attainable in high speed warp knitting machines.

In applying the principles of the invention in actual practice, the sizes of the balance weights, their radial distances from their axes of rotation, their angular relation to one another, and their distances apart will vary, depending on the details of construction of the particular machine in which they are employed. By way of example, we may point out that in one warp knitting machine, the desired reduction in vibration was obtained by mounting two three pound balance weights on the hand wheel shaft designated 54 in Fig. 3. These weights were spaced 87" apart, were in phase, and were mounted to rotate on a 3.5" radius. A harmonic couple was used, consisting of two weights of 13.5 ounces each mounted 180° apart on a shaft corresponding to that designated 61. These weights rotated on a radius of 2 $\frac{7}{16}$ " and were spaced apart 10.5". When the machine was operated with the cam shaft turning at about 400 R. P. M. and the balance weights revolving at twice the cam shaft speed, the vibrational forces produced were such as to effect substantial reduction of the vibrations produced by the non-rotary motions of the knitting assemblies. As a result, the machine operated smoothly and efficiently.

In the machine illustrated, the driving means of the machine shown is a motor belted to the hand wheel shaft, but it is to be understood that any other suitable means may be used. For example, the cam shaft may be driven directly from the driving means and the hand wheel shaft driven at the proper speed from the cam shaft. Also, as in the modification of the invention illustrated in Figure 4, the rotary balancing means may take the form of one or more discs 68 free to rotate on the cam shaft 36 and carrying balance weights 69. The motor 50 drives the hand wheel shaft 54 by any convenient means, as, for example, by sprockets or pulleys 51, 53 and belt or chain 52 and sprocket 70 fast on the hand wheel shaft is connected by a chain 71 to a sprocket 72 fast to the disc 68. The ratio of the sprockets 70 and 72 is such that the disc 68 may be driven at a multiple of the cam shaft speed to cause the balance weights 69 to produce forces that will substantially reduce the component of double frequency produced by the nonrotary movements of the knitting assemblies.

If an operating speed is desired in the range

of the third harmonic, a rotary balancing mechanism including suitable balance weights and driven at three times the cam shaft speed may be incorporated in the machine. These weights may be adjusted in angular relation to each other and at suitable distances from their centers of rotation to produce forces tending to neutralize the component of the third harmonic resulting from the increased speed of the machine.

The apparatus of the invention thus affords an easy and practical way of producing vibrational forces that substantially neutralize the vibrations set up by the nonrotary motions of the knitting assemblies at high speeds. The new balancing devices may be applied to any flat warp knitting machine more advantageously and at a lower cost of installation, than the prior devices and the use of the invention affords the further advantage that one or more guide bars may be employed in the knitting machine without the necessity of changing the balance weights every time the number of bars is changed in accordance with the requirements of the pattern.

We claim:

1. In a knitting machine, the combination of knitting elements, a rotary cam shaft, cams mounted on the shaft and imparting non-rotary knitting movements to the respective knitting elements, drive means for rotating the cam shaft, rotary balancing means operable to apply vibrational forces to the machine tending to neutralize the vibrational forces produced by the non-rotary movements of the knitting elements, and means for rotating the balancing means at a multiple of the cam shaft speed.

2. In a knitting machine, the combination of knitting elements, a rotary cam shaft, cams mounted on the shaft and imparting non-rotary knitting movements to the respective knitting elements, drive means for rotating the cam shaft, rotary balancing means operable to apply vibrational forces to the machine tending to neutralize the vibrational forces produced by the non-rotary movements of the knitting elements, said balancing means including balancing weights, and means for operating the balancing means.

3. In a knitting machine, the combination of knitting elements, a rotary cam shaft, cams mounted on the shaft and imparting non-rotary knitting movements to the respective knitting elements, drive means for rotating the cam shaft, rotary balancing means operable to apply vibrational forces to the machine tending to neutralize the vibrational forces produced by the non-rotary movements of the knitting elements, said balancing means including weights mounted for revolution about an axis, and means for revolving the weights.

4. In a knitting machine, the combination of knitting elements, a rotary cam shaft, cams mounted on the shaft and imparting non-rotary knitting movements to the respective knitting elements, drive means for rotating the cam shaft, rotary balancing means operable to apply vibrational forces to the machine tending to neutralize the vibrational forces produced by the non-rotary movements of the knitting elements, said balancing means including a shaft and weights mounted thereon, and means for rotating the shaft of the balancing means.

5. In a knitting machine, the combination of knitting elements, a rotary cam shaft, means for rotating the cam shaft, cams mounted on the

shaft and operating to impart non-rotary knitting movements to the respective knitting elements, a pair of balancing devices, each including weights mounted for revolution, the devices tending to neutralize the vibrational forces produced by the non-rotary movements of the knitting elements, and means for driving the balancing devices.

6. In a knitting machine, the combination of 10 knitting elements, a rotary cam shaft, means for rotating the cam shaft, cams mounted on the shaft and operating to impart non-rotary knitting movements to the respective knitting elements, a pair of balancing devices, each including 15 weights mounted for revolution, the devices tending to neutralize the vibrational forces produced by the non-rotary movements of the knitting elements, and means for driving the balancing devices, the weights of one device being revolved at 20 a multiple of the speed of said cam shaft.

7. In a knitting machine, the combination of 25 knitting elements, a rotary cam shaft, means for rotating the cam shaft, cams mounted on the shaft and operating to impart non-rotary knitting movements to the respective knitting elements, a rotary balancing device including balance weights revoluble about an axis, and means for driving said device and causing said weights to produce second period vibrational forces tending 30 to neutralize the second period component of the vibrational forces produced by the non-rotary motions of the knitting elements.

8. In a knitting machine, the combination of 35 knitting elements, a rotary cam shaft, cams mounted on said shaft and imparting non-rotary knitting movements to the respective elements, driving means for rotating the cam shaft including a hand wheel shaft, and a balancing device driven from the hand wheel shaft, said device including revoluble weights and being effective 40 to produce vibrational forces tending to neutralize the vibrational forces produced by the non-rotary movements of the knitting elements.

9. In a knitting machine, the combination of 45 knitting elements, a rotary cam shaft, cams mounted on said shaft and imparting non-rotary knitting movements to the respective elements, driving means for rotating the cam shaft including a hand wheel shaft, balance weights on the 50 hand wheel shaft, an auxiliary rotary balancing means, and driving means for actuating the auxiliary balancing means, the weights and auxiliary balancing means producing vibrational forces tending to neutralize the vibrational forces produced by the non-rotary movements of the knitting elements.

10. In a knitting machine, the combination of 55 knitting elements, a rotary cam shaft, cams mounted on said shaft and imparting non-rotary knitting movements to the respective elements, driving means for rotating the cam shaft including a hand wheel shaft, balance weights on the hand wheel shaft, an auxiliary rotary balancing device including revoluble weights, and means for 60 operating the auxiliary rotary balancing device, the balance weights and device producing vibrational forces tending to neutralize the vibrational forces produced by the non-rotary movements of the knitting elements.

70 11. In a knitting machine, the combination of knitting elements, a rotary cam shaft, cams mounted on said shaft and imparting non-rotary movements to the knitting elements, driving means for the cam shaft, balancing means oper- 75 able to produce vibrational forces tending to neu-

tralize the vibrational forces produced by the non-rotary movements of the knitting elements, said balancing means including weights mounted on the cam shaft for free revolution relative thereto, and means for driving the balancing 5 means.

12. In a knitting machine, the combination of knitting elements, a rotary cam shaft, cams mounted on said shaft and imparting non-rotary movements to the knitting elements, driving 10 means for the cam shaft, balancing means operable to produce vibrational forces tending to neutralize the vibrational forces produced by the non-rotary movements of the knitting elements, said balancing means including a shaft and weights 15 thereon, and means for rotating the shaft of the balancing means at a speed which is a multiple of that of the cam shaft.

13. In a knitting machine, the combination of 20 knitting elements, including thread guides and a bar supporting the guides, means for imparting non-rotary movements to the knitting elements, said means including a rotary cam shaft, cams mounted thereon, a rock shaft driven from the cam shaft, and connections between the rock 25 shaft and the thread guide supporting bar, a balancing device including a shaft mounted for rotation in proximity to said rock shaft and weights mounted thereon, said device being operable to produce vibrational forces tending to neutralize 30 the vibrational forces resulting from the non-rotary movements of the knitting elements, and means for rotating the shaft of the balancing device.

14. In a knitting machine having knitting 35 elements, a rotary cam shaft, cams mounted on the shaft and operating to impart non-rotary knitting movements to the respective knitting elements and means for rotating the cam shaft, the combination of a balancing device including 40 weights mounted for revolution and operable to produce vibrational forces tending to neutralize the vibrational forces produced by the non-rotary movements of the knitting elements, and means for driving the balancing device. 45

15. In a knitting machine having knitting elements, a rotary cam shaft, cams mounted on the shaft and operating to impart non-rotary knitting movements to the respective knitting elements, and means for rotating the cam shaft, the 50 combination of a pair of balancing devices operable to produce vibrational forces tending to neutralize the vibrational forces produced by the non-rotary movements of the knitting elements, the devices including weights mounted for revolution, and means for causing the weights of the 55 devices to revolve.

16. In a knitting machine having knitting elements, a rotary cam shaft, cams mounted on the shaft and operating to impart non-rotary knitting 60 movements to the respective knitting elements, and means for rotating the cam shaft, the combination of a balancing device including a shaft and weights thereon, the device being operable to produce vibrational forces tending to neutralize 65 the vibrational forces produced by the non-rotary movements of the knitting elements, and means for rotating the shaft of the balancing device.

17. In a knitting machine having knitting 70 elements, a rotary cam shaft, cams mounted on the shaft and operating to impart non-rotary knitting movements to the respective knitting elements, and means for rotating the cam shaft, the combination of a pair of balancing devices oper- 75

able to produce vibrational forces produced by the non-rotary movements of the knitting elements, each device including a shaft mounted for rotation and weights secured to the shaft, 5 and means for rotating the shafts of the balancing devices.

18. In a knitting machine, the combination of knitting elements, a rotary cam shaft, cams mounted on the shaft and imparting non-rotary 10 knitting movements to the respective knitting

elements, drive means for rotating the cam shaft, and means for applying to the machine as a whole vibrational forces tending to neutralize the vibrational forces produced by the non-rotary movements of the knitting elements, said means 5 including rotary elements rotated at a speed different from that of the cam shaft.

WILLIAM D. KELLOGG.
JOHN FRADENBURGH. 10
